(57) CLAIM

The ornamental design for a disposable non-woven cleaning wipe, as shown and described.

DESCRIPTION

FIG. 1 is a perspective view of one embodiment of a disposable non-woven cleaning wipe, embodying the new design;

FIG. 2 is a rear view thereof, the opposite front view is a mirror image thereto;

FIG. 3 is a left view thereof;

FIG. 4 is a right view thereof;

FIG. 5 is a top view thereof; and,

FIG. 6 is a bottom view thereof.

The broken lines shown in the drawings are for illustrative purposes only and form no part of the claimed design.
